[57] CLAIM

The ornamental design for a fishing lure, as shown.

DESCRIPTION

FIG. 1 is a left side elevational view of a fishing lure showing my new design, the right side view of the fishing lure being the same in appearance;

FIG. 2 is a top plan view of the fishing lure;

FIG. 3 is a front view of the fishing lure;

FIG. 4 is a rear view of the fishing lure;

FIG. 5 is a bottom view of the fishing lure, at reduced scale; and,

FIG. 6 is a right front elevational perspective view of the fishing lure.
